UNITED STATES PATENT OFFICE.

LOUIS T. WEISS, OF NEW YORK, N. Y., ASSIGNOR TO ALFRED A. URY, OF NEW YORK, N. Y.

GAS-CHECK FOR BUNSEN BURNERS.

SPECIFICATION forming part of Letters Patent No. 732,981, dated July 7, 1903.

Application filed November 7, 1902. Serial No. 130,377. (No model.)

To all whom it may concern:

Be it known that I, LOUIS T. WEISS, a citizen of the United States, and a resident of the city of New York, borough of Brooklyn, county of Kings, and State of New York, have invented a new and useful Improvement in Gas-Checks for Bunsen Burners, of which the following is a description, that will enable others skilled in the art to make and use the same.

The object of my invention is to improve upon the check shown and described in the copending application of Alfred A. Ury, Serial No. 118,587, and this I accomplish by means of a spring-pressed slide which may be moved to control the amount of gas which is permitted to flow into the burner, the improvement for the most part residing in the means for securing and adjusting the spring and slide to the burner-tube.

For a more detailed description of the best embodiment of my invention known to me reference is to be had to the drawings forming a part of this specification, in which—

Figure 1 is an elevation of a portion of the tube and nipple provided with my improvement. Fig. 2 is a similar view of the same, taken at right angles to Fig. 1. Fig. 3 is a section on the line 3 3, Fig. 2, looking in the direction of the arrows. Fig. 4 is a view similar to Fig. 3, except that the slide is shown partially closed. Fig. 5 is an elevation of the tube. Fig. 6 is a plan of the spring. Fig. 7 is a plan of the slide. Fig. 8 is an edge view of the spring. Fig. 9 is a plan of the screw-plug at the bottom of the tube. Fig. 10 is an elevation, and Fig. 11 is a cross-section, of the same, taken on the line 11 11 of Fig. 10 looking in the direction of the arrows.

Throughout the various views similar reference characters designate similar parts.

The lower portion of a Bunsen-burner tube is designated by the character 1, and adjacent to the lower end of this tube are the usual openings 2 and 3, through which air is admitted to the tube. These openings are substantially rectangular, except that the openings 2 are provided with enlargements 4 and 5 in their lower portions, forming the projections 6 and 7, as is clearly shown in Fig. 5. While I have shown and described two en-

largements 4 and 5, it is not necessary to have more than one. Below the openings 2 and 3 are the internal screw-threads 8, which are indicated in dotted lines in Fig. 2. The upper portion of the tube is not shown, as that forms no part of my invention, which may be applied to any Bunsen burner or similar article, and I preferably apply my improvement to those Bunsen burners which are used with Welsbach incandescent gas-lamps.

The spring 9 rests against the shoulder 6 in the upper portion of the enlargement 4, and this spring is provided with shoulders or projections 10, which closely fit the bore of the tube, as shown in Figs. 3 and 4, and these shoulders divide the spring into portions of unequal breadth, the greater not exceeding the length of the enlargements 5, and the lesser closely fits the enlargements 4, and in the center of the spring is a perforation 11. The spring 9 is a leaf-spring, which may be made out of any suitable material and is bent, as shown in Fig. 8.

In Fig. 7 is shown the slide 12, which is preferably made out of a flat piece of metal and provided with a central perforation 13 and shoulders or projections 14. The shape of the slide is substantially that of the spring, except that it is straight and not bent and is longer than the spring, and the shoulders 14 on the same edge are nearer together than the corresponding shoulders 10 of the spring in order that the slide 12 may be moved in the direction of its length in the bore of the tube.

A screw nipple or plug 15 with threads 16 engages the threads 8 in the end of the bore of the tube 1. Below the threads 16 the nipple is enlarged at 17 to form the shoulder 18, against which the lower end of the tube rests, and its upper surface 19 is a plane which forms a bearing for the slide 12. In the center of the surface or seat 19 is an opening 20, which connects with the hollow interior 21 of the plug, and on the walls of this interior are threads 22, which enable the burner to be secured to any suitable gas-fixture.

23 is a set-screw which engages the threads 16 of the plug or nipple 15, thus securing said nipple in any desired position.

The parts are assembled in the following

manner: The spring 9 is passed into the enlargement 5 of the tube 1 until the shoulders 10 are clear of the projections 7 and then it is forced upwardly until it rests transversely 5 of the tube against the projections 6, the ends of the spring flaring upwardly and outwardly. The slide 12 is then inserted in a similar manner and moved upwardly until it rests against the lower convexed surface of the spring 9. 10 The plug or nipple 15 is inserted and screwed to its proper position, as indicated in Figs. 1 and 2, thus securing all the parts in their proper positions, so that the openings 20 and 11 will always register, and the opening 13 may 15 be moved either into or out of alinement with them, as shown in Figs. 3 and 4, or into any intermediate position, thus forming between the slide 12 and surface 19 a valve which will regulate by the size of the opening the amount 20 of gas that enters the tube. The tension on the spring 9 may be adjusted by turning the plug or nipple 15 so that the slide 12 is forced into more or less intimate contact with the spring 9 and so moves with greater or less 25 freedom on the surface 19.

An advantage of this construction is that the gas issues through the reduced opening with increased velocity, thus forming a jet which draws air with greater facility through 30 the openings 2 and 3. This advantage would not be obtained if the passages were crooked or tortuous, as is the case where gas is regulated by an ordinary cock.

While I have shown and described the best 35 known embodiment of my invention, I wish it to be understood that many other forms are conceivable, which are covered in the following claims.

I claim—

- 40 1. In a gas-check or similar article, a tube, a spring laterally secured to the same, and spring - controlled and laterally - movable means connected with the spring to regulate the flow of gas through the check.
- 45 2. In a gas-check or similar article, a tube, a spring laterally secured to the same, a spring-controlled and laterally-sliding means connected with the spring to regulate the flow of gas through the check.
- 50 3. In a gas-check or similar article, a tube, a spring secured to the same, and a slide pressed by said spring and regulating the flow of gas through the check.
- 55 4. In a gas-check or similar article, a tube and a spring secured to the said tube, a slide and a seat, said spring tending to press said slide against said seat.
- 60 5. In a gas - check, a tube, a perforated spring secured thereto, a slide and a bearing for said slide.
- 65 6. In a gas-check or similar article, combination of a tube, a seat secured thereto, a perforated slide moving on said seat, and a spring pressing said slide and surface together.
- 70 7. In a gas-check or similar article, a tube, a spring secured thereto, a slide and a per-

forated seat, said slide resting between said perforated seat and spring.

8. In a gas-check or similar article, a tube 70 with a perforated spring secured thereto, a seat and a perforated slide between said spring and seat.

9. In a gas-check or similar article, a tube with a perforated spring secured thereto, a 75 perforated seat beneath said spring and a slide between said spring and seat.

10. In a gas-check or similar article, a tube with a spring secured thereto, a perforated seat beneath said spring, and a perforated 80 slide between said spring and seat.

11. In a gas-check or similar article, a tube with a perforated spring secured thereto, a perforated seat beneath said spring and a 85 perforated slide between said spring and seat.

12. In a gas-check or similar article, a tube, a perforated spring secured thereto, a perforated slide beneath said spring, a perforated nipple screwed into said tube, the upper portion of said nipple forming a bearing-surface 90 for said slide.

13. As an article of manufacture, a tube for Bunsen burners and the like, provided with openings and projections in said openings, and a spring and sliding bearing against 95 said projections.

14. As an article of manufacture, a tube for Bunsen burners and the like, provided with openings, projections in said openings against which a spring and slide may rest 100 and screw-threads formed in said tube adjacent to said openings.

15. In a gas-check or similar article, a tube provided with openings, projections in said openings, a spring seated against said projections, and means for securing said spring 105 in place.

16. In a gas-check or similar article, a tube provided with openings, projections in said openings, and a spring and a slide engaging 110 said projections.

17. In a gas-check or similar article, a tube provided with openings, projections in said openings, a spring and slide engaging said projections against which the slide is pressed 115 by the spring.

18. In a gas-check or similar article, a tube with openings, with projections therein, a spring and a slide engaging said projections, and a nipple in said tube securing the slide 120 and spring in place.

19. In a gas-check or similar article, a tube with a spring secured thereto, and means external to said tube for changing the tension of the spring.

20. In a gas-check or similar article, a tube with a spring secured thereto, and rotary means external to said tube for changing the tension of the spring.

21. In a gas-check or similar article, a tube 130 with a spring secured thereto, and a nipple for changing the tension of the spring.

22. In a gas-check or similar article, a tube with openings therein, a spring resting in

said openings, and projections on said spring engaging the walls of said tube.

23. In a gas-check or similar article, a tube with openings therein, a slide resting in said openings, and projections on said slide which limit its movement by engaging the walls of said tube.

24. In a gas-check or similar article, a tube with openings, a spring with projections resting in said openings, the projections engaging the walls of the tube, and a slide also resting in said openings.

25. In a gas-check or similar article, a tube with openings, a spring with projections resting in said openings, the said projections en-

gaging the walls of said tube, a slide engaging said spring and tube, and projections on said slide which limit its movement by engaging the walls of said tube.

26. In a gas-check or similar article, a tube, a spring secured thereto, a slide, a plug pressing said slide against said spring, and means for securing said plug against rotation.

In testimony whereof I set my hand, this 1st day of November, 1902, in presence of two subscribing witnesses.

LOUIS T. WEISS.
